UNITED STATES PATENT OFFICE.

EDWARD J. GROSS, OF NEW ROCHELLE, NEW YORK, ASSIGNOR TO BENJAMIN &
EDWARD J. GROSS CO., INC., OF NEW YORK, N. Y.

DESIGN FOR A FINGER RING OR SIMILAR ARTICLE.

Application filed February 6, 1929. Serial No. 29,957. Term of patent 3½ years.

To all whom it may concern:

Be it known that I, EDWARD J. Gross, a citizen of the United States, residing in New Rochelle, in the county of Westchester and State of New York, have invented a new, original, and ornamental Design for a Finger Ring or Similar Article, of which the following is a specification, reference being had to the accompanying drawing, forming a part thereof.

The figure is a perspective view of a finger ring showing my new design.

I claim:

The ornamental design for a finger ring or similar article, as shown.

In testimony whereof I affix my signature.

EDWARD J. GROSS.
